UNITED STATES PATENT OFFICE.

FRANK J. CLARK, OF MILWAUKEE, WISCONSIN.

SHEET-GUIDE FOR PNEUMATICALLY-ACTUATED MECHANISM.

1,158,639.

Specification of Letters Patent.

Patented Nov. 2, 1915.

Application filed November 27, 1914. Serial No. 874,106.

To all whom it may concern:

Be it known that I, FRANK J. CLARK, a citizen of the United States, and resident of Milwaukee, in the county of Milwaukee and 5 State of Wisconsin, have invented certain new and useful Improvements in Sheet-Guides for Pneumatically-Actuated Mechanism; and I do hereby declare that the following is a full, clear, and exact description thereof.

My invention consists in what is herein particularly set forth with reference to the accompanying drawings and pointed out in the claims of this specification, its object being 10 to provide simple, economical, highly sensitive and efficient means by which to insure correct travel of a perforated sheet across the tracker-bar of a pneumatic piano player or other pneumatically actuated mechanism, whereby registration of all the 15 perforations in the sheet is had with corresponding air-ducts in said tracker-bar.

Figure 1 of the drawings represents a front elevation partly in section and it illustrates 20 an application of my improved means for guiding a perforated sheet across the tracker-bar of a pneumatically actuated mechanism, Fig. 2, a plan view partly in horizontal section on the plane indicated by line 2-2 in 25 Fig. 1, and Fig. 3, a sectional view of a detail, this view being indicated by line 3-3 in Fig. 2.

Referring by numerals to the drawings, 30 indicates a tracker-bar such as is usually employed in the spool-box of a pneumatic piano-player or other pneumatically actuated mechanism, 5 the spring-controlled head-stock and 6 the tail-stock for the spool 35 7 of a perforated sheet 8 that unwinds from said spool onto a take-up roller 9, the travel of said sheet being across the tracker-bar close against the same. To attain entirely 40 satisfactory results, all the perforations of the traveling sheet must coincide with air-ducts of the tracker-bar and the automatic sheet-guide mechanism hereinafter specified is effective for that purpose.

Supported in connection with the tracker-bar or otherwise suitably arranged is a cylindrical chamber 10 open at one end to atmosphere, and one or more ports 11 in the wall of the chamber are controlled by a rotary reciprocative valve 12. A lever branch 13 of the valve has play in slots provided 45 in said chamber and tracker-bar. A lug of

the lever 13 is shown connected to a rod 14 coupled, by a turn-buckle 15, to another rod 16 in connection with a lug of another lever 17. The lever 17 is shown fulcrumed in connection with the tracker-bar and extends 60 outward, at the front, through a slot in the same.

The sheet 8 unwinding from the spool 7 onto the take-up roller 9 travels between the levers 13 and 17, but not in constant contact 65 with either, and the chamber-ports 11 are in communication with a tube 18 fitted in an outer socket-lug 19 of the chamber-wall. An air-hose 20 is shown connecting the tube 18 with a tube 21 extending from a cell 22 in a 70 vacuum-block 23. The space 22 in the block is partitioned from the vacuum-cell 24 also therein by a diaphragm 25 having a bleed opening 26 therein, and fitted in a port of the same cell is a tube 28 in an end of an air-hose 29 that leads from a source of vacuum. The vacuum-cell 24 has a port 30 open to a 75 bellows 31, and the diaphragm 25 is connected to the stem 32 of valves 33, 34, controlling opposite ports of a passage 35 in the block 23, this passage being in communication with another bellows 36 of greater air capacity than the one aforesaid, the difference of air capacity of the two bellows being an important feature of my invention. 80

The two bellows are connected by a link 37, and the bellows 31 of least air capacity is connected, by a link 38, with an arm 39' of a cam 39 having pivotal connection with a bracket 40 on a wall of the aforesaid spool-box, and the cam opposes the tail-stock 6 for the sheet-spool. 85

The operation of my invention, as thus far disclosed, is as follows: The valve 12 in the chamber 10 is moved to open or close the 90 chamber outlet as a result of lateral shifting of the traveling sheet 8 against the levers 13 and 17. Said outlet being open to atmosphere, the vacuum in the cell 24 is exerted upon the diaphragm 25 to lift the 95 valves 33 and 34, thus cutting off the passage 35 from said cell and opening said passage to atmosphere. At the same time the vacuum is exerted upon the bellows 31, and the collapsing of this bellows results in a 100 throw of the cam 39 in a direction to permit movement of the sheet-spool toward the right, thus permitting the sheet to attack the lever 17 and effect a closing of the chamber-outlet by the valve 12. This results in 105 110

a bleed of air from the cell 22 in the block 23 and a drop of the valves 33 and 34, whereby the passage 35 is closed to atmosphere and opened to vacuum that causes a collapsing of the bellows 36 and a distension of the bellows 31 to throw the cam 39 in a direction to cause movement of the sheet-spool toward the left, the distension of said bellows 31 being due to the greater air capacity of said bellows 36. The movement of the perforated sheet being vibratory across the tracker-bar, all of the perforations of said sheet are caused to register with air-ducts of said bar. In case a portion of the sheet is torn out at an edge of the same, the break in the continuity of such edge will pass the opposing lever and there can be no sheet-pressure on said lever during the time said break is passing. The lever 17 opposing an edge of the traveling sheet and in link connection with the lever 13 is one means by which to govern the movement of the valve 12, but without departure from my invention, as herein claimed, other means for the same purpose may be substituted. Happening that there are imperfect perforated sheets that need tracking farther to the right or left, the head of the chamber 10 is centrally pivoted in connection with the tracker-bar, and a lateral arm 41 of said chamber is provided with a pivotal nut 42 engaged by an adjusting screw 43 for which the tracker-bar is provided with a bearing, a milled head of the screw being shown forward of said bar. Hence the aforesaid chamber may be readily adjusted with respect to the valve 12 to compensate at the start for an imperfect perforated sheet that has travel across the tracker-bar. The levers 13 and 17 are adjustably connected, by the turn-buckle union 15 of the rods 14 and 16, to provide for compensating for shrinkage or swelling of the perforated traveling sheet.

45 I claim:

1. In a guide-mechanism for a perforated sheet having travel across a tracker-bar of a pneumatically actuated mechanism, a pair of mechanically connected bellows of different air capacity one of which is constantly open to vacuum, the other intermittently under the influence of vacuum and both in communication when the one of greatest air capacity is open to the vacuum; and means whereby said bellows of greatest air capacity is controlled with reference to vacuum influence as a result of lateral shift of said sheet on said tracker-bar.

2. In a guide-mechanism for a perforated sheet having travel across a tracker-bar of a pneumatically actuated mechanism, a pair of connected bellows of different air capacity, a block having a vacuum cell therein in constant communication with the bellows of least air capacity, and a valve controlled

passage between said cell and the bellows of greatest air capacity, another cell in the block separated from the one aforesaid by a diaphragm provided with a bleed opening and connected to valves governing said passage, means under the influence of the traveling sheet governing the opening and closing of the last named cell to atmosphere, and means in connection with said bellows of least air capacity governing endwise movement of a suspended spool from which said sheet is unwound.

3. In a guide-mechanism for a perforated sheet having travel across a tracker-bar of a pneumatically actuated mechanism, a pair of connected bellows of different air capacity, a block having a vacuum cell therein in constant communication with the bellows of least air capacity and a valve controlled passage between said cell and the bellows of greatest air capacity, another cell in the block separated from the one aforesaid by a diaphragm provided with a bleed opening and connected to valves governing said passage, a suitably arranged cylindrical chamber open at one end to atmosphere and having outlet in communication with the cell last aforesaid, a rotary reciprocal valve in the chamber controlling the outlet therefrom, a valve-shifting mechanism to which the sheet has edgewise opposition, and means in connection with the bellows of least air capacity governing endwise movement of a suspended spool from which said sheet unwinds.

4. In a guide-mechanism for a perforated sheet having travel across a tracker-bar of a pneumatically actuated mechanism, a pair of connected bellows of different air capacity, a block having a vacuum cell therein in constant communication with the bellows of least air capacity and a valve controlled passage between said cell and the bellows of greatest air capacity, another cell in the block separated from the one aforesaid by a diaphragm provided with a bleed opening and connected to valves governing said passage, a suitably arranged cylindrical chamber open at one end to atmosphere and having outlet in communication with the cell last aforesaid, a rotary reciprocal valve in the chamber controlling the outlet therefrom, a valve-shifting mechanism to which the sheet has edgewise opposition, a lever extending from the valve to oppose an edge of the sheet, another lever arranged to oppose the other edge of said sheet, a link connecting the levers, and means in connection with the bellows of least air capacity for governing endwise movement of a suspended spool from which the aforesaid sheet is unwound.

5. In a guide-mechanism for a perforated sheet having travel across a tracker-bar of a pneumatically actuated mechanism, a pair of

- connected bellows of different air capacity, a block having a vacuum cell therein in constant communication with the bellows of least air capacity and a valve controlled passage between said cell and the bellows of greatest air capacity, another cell in the block separated from the one aforesaid by a diaphragm provided with a bleed opening and connected to valves governing said passage, a suitably arranged cylindrical chamber open at one end to atmosphere and having outlet in communication with the cell last aforesaid, a rotary reciprocative valve in the chamber controlling the outlet therefrom, a valve-shifting mechanism to which the sheet has edgewise opposition, a cam arranged in opposition to the tail-stock for the spool from which said sheet is unwound, and a link connecting the cam with the bellows of least air capacity.
6. In a guide-mechanism for a perforated sheet having travel across a tracker-bar of a pneumatically actuated mechanism, a pair of connected bellows of different air capacity, a block having a vacuum cell therein in constant communication with the bellows of least air capacity and a valve controlled passage between said cell and the bellows of greatest air capacity, another cell in the block separated from the one aforesaid by a diaphragm provided with a bleed opening and connected to valves governing said passage, a suitably arranged pivotally adjustable cylindrical chamber open at one end to atmosphere and having outlet in communication with the cell last aforesaid, a rotary reciprocative valve in the chamber controlling the outlet therefrom, a valve-shifting mechanism to which the sheet has edgewise opposition, and means in connection with the bellows of least air capacity governing endwise movement of a suspended spool from which said sheet unwinds.
7. In a guide-mechanism for a perforated sheet having travel across a tracker-bar of a pneumatically actuated mechanism, a pair of connected bellows of different air capacity, a block having a vacuum cell therein in constant communication with the bellows of least air capacity and a valve controlled pas-
- sage between said cell and the bellows of greatest air capacity, another cell in the block separated from the one aforesaid by a diaphragm provided with a bleed opening and connected to valves governing said passage, a cylindrical chamber in pivotal connection with a support and open at one end to atmosphere, an arm extending from the chamber, an adjusting screw in connection with the arm, a rotary reciprocative valve in the chamber controlling the outlet therefrom, a valve-shifting mechanism to which the sheet has edgewise opposition, and means in connection with the bellows of least air capacity governing endwise movement of a suspended spool from which said sheet unwinds.
8. In a guide-mechanism for a perforated sheet having travel across a tracker-bar of a pneumatically actuated mechanism, a pair of connected bellows of different air capacity, a block having a vacuum cell therein in constant communication with the bellows of least air capacity and a valve controlled passage between said cell and the bellows of greatest air capacity, another cell in the block separated from the one aforesaid by a diaphragm provided with a bleed opening and connected to valves governing said passage, a suitably arranged cylindrical chamber open at one end to atmosphere and having outlet in communication with the cell last aforesaid, a rotary reciprocative valve in the chamber controlling the outlet therefrom, a pair of valve shifting levers between which the sheet travels, means by which said levers are adjustably connected, and means in connection with the bellows of least air capacity governing endwise movement of a suspended spool from which said sheet unwinds.

In testimony that I claim the foregoing I have hereunto set my hand at Milwaukee in the county of Milwaukee and State of Wisconsin in the presence of two witnesses.

FRANK J. CLARK.
